Attorney

UNITED STATES PATENT OFFICE.

MIKE LUTENBERGER, OF BLOCTON, ALABAMA.

BOTTLE.

1,136,250.

Specification of Letters Patent. Patented Apr. 20, 1915.

Application filed July 1, 1914. Serial No. 848,478.

To all whom it may concern:

Be it known that I, MIKE LUTENBERGER, a subject of the King of Hungary, residing at Blocton, in the county of Bibb and State 5 of Alabama, have invented certain new and useful Improvements in Bottles, of which the following is a specification, reference being had therein to the accompanying drawing.

10 This invention relates to certain new and useful improvements in bottles especially adapted to be used for dispensing carbonated beverages, the object being to provide a bottle with a valve by means of which the 15 same can be readily closed after the bottle has been filled with a carbonated beverage such as beer, and the like.

Another and further object of my invention is to provide a bottle which is exceedingly simple and cheap in construction, the 20 valve being so formed and arranged within the neck of the bottle, that an exceedingly tight joint is formed between the valve casing and the neck in order to prevent the carbonated gas from escaping after the bottle 25 has been filled.

Other and further objects and advantages of the invention will be hereinafter set forth and the novel features thereof defined by 30 the appended claims.

In the drawings—Figure 1, is a side elevation of a portion of a bottle constructed in accordance with my invention, showing the same used in connection with what is known 35 as a “home bottler”; Fig. 2, is a vertical section through the neck of the bottle; and Fig. 3, is a vertical section taken at right angles to that of Fig. 2.

Like numerals of reference refer to like 40 parts in the several figures of the drawings.

In the drawings, 1 indicates an ordinary cask such as a beer keg, 2 the faucet extending therefrom, to which is connected the home bottling apparatus 3 by means of 45 which, the carbonated beverage contained within the keg is conveyed to the bottle to be filled, the above description being given, so that the advantages of providing a bottle with a valve as constructed by applicant, can 50 be clearly understood.

In carrying out my invention, I employ a bottle 4 of the ordinary shape having a neck 5 provided with an annular interior enlargement 6 through which extends transversely, 55 a tapering bore 7 which is surrounded upon the outer faces of the neck, by annular re-

cesses 8 and 9, for the purpose hereinafter described. The annular enlargement 6 is provided with tapering faces as clearly shown in Figs. 2 and 3, in order to avoid 60 forming any abrupt obstructions within the mouth of the bottle so that liquid will pass readily through the neck of the bottle into the body thereof. Inserted in the transverse bore 7 formed in the neck of the bottle, is a 65 tapering sleeve 10 forming a valve casing, said sleeve being provided with a flanged end 11 which fits within the recess 9 formed in the outer face of the bottle neck and after the casing has been forced into position, the end is swaged so as to form an 70 annular flange 12 which is seated within the annular recess 8 in order to securely lock the casing in position within the bottle in order to form an air-tight joint, this being 75 obtained by the wedging action of the tapering valve casing within the tapering bore.

The valve casing is provided with oppositely disposed openings 13 and 14 communicating respectively with the body and 80 mouth of the bottle as clearly shown in Figs. 2 and 3 through which the liquid is adapted to pass. Arranged within the valve casing 10 is a tapering valve plug 15 which is provided with a transverse bore or opening 16 85 adapted to register with the openings 13 and 14 in order to form a passage to allow the liquid to pass into the bottle and out of the same. The tapering valve plug fits snugly within the tapering valve casing and forms 90 an air-tight seat between the walls thereof. The plug is provided with a threaded stem 17 at one end over which is arranged a washer 18 which fits within an annular enlargement 19 formed in the end of the valve 95 casing, said washer engaging the shoulder formed by the enlargement in order to prevent the plug from moving outwardly after the same has been arranged in position and for locking the washer to the plug, I provide 100 an ordinary nut 20 which is secured in position upon the threaded stem 17 as shown in Fig. 3. The opposite end of the plug is provided with a key-receiving socket 21 in which a suitable key is adapted to be inserted 105 for rotating the valve plug within the casing in order to open and close the valve.

In the operation of my improved construction of bottle in connection with a home bottler as shown in Fig. 1, the valve plug is rotated until the openings register with the 110 openings of the valve casing and the home

bottler is inserted within the mouth of the bottle and when the bottle has become filled with the carbonated beverage, the valve plug is rotated so as to close the openings 13 and 14.

By this construction, the disadvantages of using caps and the like are dispensed with and a bottle is provided which is so constructed that the beverage will be maintained 10 within the same in the same condition that it is in when inserted, which enables a person to bottle beer and the like, from a cask for home purposes.

I am aware that bottles have been constructed previous to my invention, with valves which are carried by detachable neck members, but in no instance am I aware that a bottle has been provided with its neck formed with a bore in which the valve casing 15 is seated carrying a valve which enables the bottle to be manufactured very cheaply.

I claim:

1. A bottle, having an integral neck having an annular enlargement provided with a 25 tapering transverse bore, a tapering valve casing arranged within said bore having oppositely disposed openings and provided with flanged ends for securing said casing within said bore, and a tapering plug provided with an opening revolvably mounted within said valve casing having a socket at one end.

2. As a new article of manufacture, a bottle having a tapering bore formed in its neck, 35 the ends of said bore being surrounded by annular recesses, a tapering valve casing arranged within said bore having annular flanges at its ends seated in said recesses, said valve casing being provided with oppo-

sitely disposed openings, and a rotary valve 40 plug mounted within said valve casing.

3. A bottle, having a neck provided with an annular interior enlargement, the walls of said neck at the point of enlargement being provided with oppositely disposed tapering bores, the outer ends of said bores being surrounded by annular recesses, a tapering sleeve forming a valve casing arranged within said bores, having annular flanges seated within said recesses at its ends, one 50 end of said sleeve being provided with an interior annular enlargement, a valve plug mounted within said valve casing provided with a threaded stem, a washer carried by said stem fitting within said annular enlargement, a nut mounted on said stem engaging said washer, said valve plug having a key-receiving socket at its opposite end for rotating said valve within said casing.

4. A beer bottle, having an integral neck, 60 the walls of which are provided with oppositely disposed tapering bores, a tapering valve casing arranged within said bores having an annular enlargement at one end, the ends of said valve casing being swaged for 65 securing said valve casing within said bore, a valve plug revolvably mounted within said valve casing, and a washer carried by one end of said valve plug fitting within the enlargement of said valve casing for preventing longitudinal movement of said valve plug.

In testimony whereof I hereunto affix my signature in the presence of two witnesses.

MIKE LUTENBERGER.
